UNITED STATES PATENT OFFICE

128,684

DESIGN FOR A RADIO TRANSMITTER

Adam E. Abel, Linthicum Heights, Md.

Application March 7, 1941, Serial No. 99,399

Term of patent 3½ years

To all whom it may concern:

Be it known that I, Adam E. Abel, a citizen of the United States, residing at Linthicum Heights, county of Anne Arundel in the State of Maryland, have invented a new, original, and ornamental Design for a Radio Transmitter, of which the following is a specification, reference being had to the accompanying drawing, forming a part thereof, in which:

Fig. 1 is a front perspective view of the radio transmitter embodying my new design; Fig. 2 is a rear elevational view; and Fig. 3 is an end elevational view taken on the right end with reference to Fig. 1.

I claim:

The ornamental design for a radio transmitter, as shown.

ADAM E. ABEL.
